UNITED STATES PATENT OFFICE.

JOHN HENDRY, OF LAWRENCE, MASSACHUSETTS, ASSIGNOR TO DRAPER COMPANY,
OF HOPEDALE, MASSACHUSETTS, A CORPORATION OF MAINE.

FEELER-MOTION FOR LOOMS.

1,081,909.

Specification of Letters Patent. Patented Dec. 16, 1913.

Application filed April 28, 1913. Serial No. 763,967.

To all whom it may concern:

Be it known that I, JOHN HENDRY, a citizen of the United States, residing at Lawrence, county of Essex, and State of Massachusetts, have invented an Improvement in Feeler-Motions for Looms, of which the following description, in connection with the accompanying drawings, is a specification, like letters on the drawings representing like parts.

10 The invention to be hereinafter described relates to filling replenishing looms, wherein a fresh supply of filling is furnished prior to complete exhaustion of that in the running shuttles, and more particularly the present invention has reference to the feeler motion of such looms.

15 As well known by those skilled in the art, feeler motion devices intermittently feel for the filling in the running shuttle, and when the desired or predetermined exhaustion of the filling has been reached, such devices are intended to cause or permit the operation 20 of the filling replenishing mechanism. One 25 of the most serious objections encountered in the use of such devices is the waste of yarn or filling caused by the operation of the filling replenishing mechanism and consequent ejection of a filling carrier while 30 there yet remains a considerable quantity of filling thereon. Moreover, such yarn or filling as remains upon the carrier when thus ejected must be removed prior to re-winding, thereby entailing further waste in 35 labor cost, substantially in proportion to the amount of yarn or filling to be removed.

40 Various forms of feeler motions or filling exhaustion indicating mechanisms have been devised, some of which have been employed in connection with a "bunch" wound upon the bobbin or carrier, others of which have depended for their operation upon contact with the bobbin itself, or a ring thereon, and some of these have operated satisfactorily in 45 their particular relations. In the patent to V. Rainville, No. 1,040,409, dated October 8, 1912, for instance, a feeler motion is shown and described, which upon substantial exhaustion of the filling, acts upon a rib or 50 abutment on the carrier to cause operation of the filling replenishing mechanism. It may sometimes happen, however, especially in certain forms of filling-wound bobbins or carriers, where for instance, the end of the 55 filling wind is conical in form, that the bob-

bin or carrier may still have considerable yarn or filling thereon sufficient for two or more picks of the shuttle, when the rib or projection on the carrier is ready to actuate the feeler motion and under such conditions it is desirable that the feeler motion should not cause operation of the filling replenishing mechanism.

60 The aims and purposes of the present invention are to provide a feeler motion for 65 looms, wherein the parts are so related that a more perfect detection of filling exhaustion may be had, and the filling replenishing mechanism may be maintained inactive so long as the bobbin or carrier contains sufficient 70 yarn or filling for the proper production of cloth, all of which will best be understood from the following description and accompanying drawings of one form of means for carrying the invention into practical effect, it being understood that details 75 may be varied within the true scope of the invention as defined by the claims.

80 In the drawings:—Figure 1 is a plan view of a filling feeler mechanism embodying the present invention, showing also part of a shuttle and filling carrier therein, and parts of the shuttle box; Fig. 2 is a section on the line 2—2, Fig. 1; Fig. 3 is an enlarged dia- 85 grammatic view showing parts of the feeler mechanism, acting upon a filling carrier, while the carrier is supplied with sufficient filling for weaving purposes; Fig. 4 shows the relation of the parts of Fig. 3 when the filling has reached that degree of exhaustion 90 at which replenishment is desirable; and Fig. 5 is an end view of the feeler mechanism looking from the left, Fig. 1.

95 In the drawings, the shuttle 1 is or may be of usual character, provided with holding jaws 2 to engage the head 3 of the removable filling carrier or bobbin 4. The front wall of the shuttle 1 has an opening or slot 5 through which the feeler device, to be described, may enter in usual manner, and similarly the front wall of the shuttle box (not shown) has an aperture with which the opening or slot 5 may register when the shuttle is properly boxed at the feeling side 100 of the loom, all as usual and well understood.

105 Mounted upon the loom frame opposite the shuttle box 6 at the feeling side of the loom is a casing 7 adapted to support the feeler slide 8 in a manner to permit such 110

slide to move longitudinally. As a convenient form for such purpose, the casing 7 is chambered at 9 for the passage of the shank 10 of the feeler slide, and surrounding 5 said shank 10 is a spring 11, one end of which bears upon the shoulder 12 of the shank, and the other upon the opposite end portion of the casing, the construction being such that the spring normally holds the 10 filling slide projected to the left, Fig. 2, but permits such slide to move longitudinally upon the application of force, as will presently appear. The casing 7 may be held in place by any appropriate means, such as by 15 the screws 13.

Extending along one side of the casing 7 is a guideway for the end portion of a transmitter 14, Figs. 1 and 2, such guideway being preferably formed by a slot 15 in a 20 flange 16 projecting from the casing 7. The parts thus far described may be substantially as set forth in the patent to Rainville, No. 1,040,409, of October 8, 1912, and may be changed to suit conditions of use. Here- 25 in it will be understood that actuation of the transmitter 14 by the feeler mechanism to be described, is designed to cause filling replenishment, but as such replenishing mechanism and the association therewith of 30 the transmitter are well understood by those skilled in the art, the details thereof are not illustrated herein.

The feeler slide 8 is extended toward the rear of the loom or toward the shuttle-box 35 and has a feeler head 17, the front face 18 of which is cut away or beveled, as indicated in Figs. 1, 3, and 4, to form a feeler toe or point 19 which, during the operation of the loom, is adapted to contact with the filling 40 20 on the bobbin or carrier 4, and by virtue of its toe or pointed character to embed itself or sink into the filling mass. In the preferred form of the invention, as exemplified by the drawings, the feeler toe or point 45 19 is formed by cutting away the front face 18 of the feeler head diagonally from a point 21, Figs. 3 and 4, and removing any bur or other roughness on the toe or point 19 that might injure the yarn or filling.

50 It will be noted by reference to Figs. 3 and 4, that the feeler toe or point 19 of the feeler head will contact with the filling on the carrier opposite a cylindrical part of the bobbin or carrier rather than at or opposite a rib or projection 22, and that such feeler toe or 55 point 19 does not extend to any material degree longitudinally of the bobbin or carrier.

Projecting from the feeler slide 8 are the lugs 23 between which is pivotally mounted 60 at 25 the lever 24, which for identification may be known as the detector or detector lever. One arm of the detector lever extends toward the front of the loom and has a shoulder 26 adapted to engage the trans-

mitter 14 when that end of the detector is depressed. From its pivotal mounting 25 the detector 24 has a rearwardly extending arm 27 carrying a detector head.

The detector head is formed of two parts 28 and 29, Figs. 3 and 4, which may be integral or otherwise joined rigidly together. The part 28 is disposed at one side of the feeler toe or point 19 and has an edge portion 30 in a plane slightly back of the end of the feeler toe or point 19. That is to say, the edge portion 30 of the detector is slightly nearer the front of the loom, than is the end of the toe or point 19, the construction being such that as the lay moves forward, the filling mass on the carrier will first meet the toe or point 19, which, being under the influence of the spring 11, will sink into the yarn mass, Fig. 1, until the latter meets the edge 30 of the head part 28, whereupon the detector will be turned upon its pivotal mounting 25 to raise the shoulder 26, and the feeler slide will then move toward the front of the loom without actuating the transmitter 14 as will be readily understood. To limit the rising movement of the shouldered portion of the detector, a suitable stop may be employed. That illustrated comprises a spring finger 31 secured to the feeler slide 8 by means of the screws 32, which may also serve to hold the lugs 23 in place. Should the yarn mass on the carrier, however, have become practically exhausted, as indicated in Fig. 4, the feeler toe or point 19 will again first meet the yarn, as at α which may be identified as the initial winding, but there being only one or two layers of yarn at this point under the assumed conditions, the toe or point 19, cannot sink far enough into the yarn to permit the edge 30 of the detector head to be met by the yarn, with the result that the forwardly moving bobbin or carrier will force the feeler slide to the front without lifting the shoulder 26 of the detector, and the latter will engage and actuate the transmitter 14 to initiate operative condition of the filling replenishing mechanism. It will be noted in this connection that the feeler toe or point 19 does not contact with a rib or projection on the bobbin or carrier, but engages the yarn or bobbin at a point closely adjacent to that which would be engaged by the edge 30 of the detector head if such engagement were possible. It will also be noted that while the edge of the detector head is extended longitudinally of the bobbin or filling carrier, the feeler toe presents only a small area or point which will readily sink into the mass of yarn load during normal operative conditions, but when the yarn or filling has become practically exhausted, as indicated at α , Fig. 4, the toe or point 19 cannot sink sufficiently far into the yarn or filling to permit contact of the detector head

with such yarn or filling, and the filling replenishing operation is initiated as above indicated.

From the construction described it will be evident that should the bobbin or carrier be so wound that the yarn or filling will be entirely exhausted from parts of the bobbin or carrier beyond the initial windings at α before the feeler mechanism acts, a minimum amount of yarn or filling may be left upon the bobbin or carrier when the filling replenishing mechanism ejects the spent bobbin or carrier. It sometimes happens, however, especially where the bobbin or carrier is wound with conical end portions as indicated by Fig. 1, that considerable yarn or filling yet remains on the bobbin or carrier at some point beyond the initial winding even after the initial winding at α has reached a degree of exhaustion that would cause the feeler mechanism to set the replenishing mechanism in condition for operation, and one of the purposes of the present invention is to detect this condition and thereupon suspend the action of the feeler mechanism until the working supply of yarn or filling has been exhausted. This condition is typified in Fig. 3, wherein it will be seen that the initial winding at α has reached a state of exhaustion that would cause the feeler mechanism to act in the absence of any means to prevent, even though there may yet remain at γ sufficient yarn or filling for working purposes.

To the end that the feeler mechanism may detect the insufficient exhaustion of the working yarn load under the conditions stated and thereupon suspend the action of the replenishing mechanism, the detector head is provided with a portion 29 which extends in a general direction longitudinally of the bobbin or carrier to the side of the feeler toe or point 19 opposite the part 28, said part 29 being adapted to detect and act upon any service windings as the lay beats up and lift the shouldered portion of the detector, so that as the feeler slide is pushed forward the transmitter will not be actuated. In the preferred form of this feature of the invention, the part 29, which for identification may be known as the indicator head, has an inclined edge portion 33 reaching from a point 34 back of the feeler toe 19 to a point 35 substantially in the plane of the edge 30 of the detector head 28, the construction being such, that should sufficient yarn or filling be present for weaving purposes beyond the initial windings at α as indicated in Fig. 3 at γ , the part 29 of the detector head will indicate the fact and tilt the detector in a manner to prevent the actuation of the transmitter 14 as the lay beats up, even though the exhaustion at the initial windings is such that the detector head 28

would not be met by the windings at that point and consequently not be tilted.

It will be noted that the edge 33 of the indicator head 29 is inclined toward the bobbin or filling carrier from a point 34, and that the end 35 is in substantially the plane 70 of the edge 30 of the detector head, so that even though the bobbin or filling carrier have the usual ribs or rings 22, the indicator head will bridge over such ribs or rings and feel for any service windings that may exist 75 beyond, as indicated by Figs. 3 and 4.

The detector head 28 extends at one side of the feeler toe 19, and in the form of the invention shown, the indicator head extends therefrom under the feeler head 17 to the opposite side, but it will be evident that the details in these respects may be variously modified. The detector normally stands with its shouldered portion 26 in position to engage the transmitter 14 should the feeler slide be moved to the right, Fig. 2, but when a working supply of filling is present on the bobbin or carrier the detector will be tilted, as indicated by Fig. 2, either by the detector head 28 or 90 by the indicator head 29, as above explained, so that on movement of the feeler slide to the right, Fig. 2, the transmitter 14 will not be actuated.

What is claimed is:

95

1. In a feeler motion for filling replenishing looms, the combination of a feeler slide having a feeler toe or point, a detector mounted on said slide and having a detector head at one side of said feeler toe or 100 point and an indicator head at the opposite side of said toe or point.

2. In a feeler motion for filling replenishing looms, the combination of a feeler slide having a feeler toe or point adapted to 105 contact with and sink into the filling on the bobbin or filling carrier, a detector pivotally mounted on said slide and having a detector head at one side of said toe or point and an indicator head at the opposite side of said 110 toe or point.

3. In a feeler motion for filling replenishing looms, the combination of a feeler slide having a feeler toe or point adapted to contact with and sink into the filling on the bobbin or filling carrier, a detector pivotally mounted on said slide and having a detector head at one side of said toe or point and an indicator head at the opposite side of said toe or point, said feeler toe or point being 115 extended beyond the edges of the detector and indicator heads.

4. In a feeler motion for filling replenishing looms, the combination of a feeler slide having a portion to contact with and sink 120 into the filling on the carrier when there is a working supply of filling opposite said portion, a detector adapted to engage the filling

when the said portion has sunk thereinto, and to be moved by said filling, and means to indicate the presence of filling beyond the point where the detector acts and to move said detector when the filling opposite thereto fails to move it and there yet remains a working supply of filling on the carrier.

5. A feeler motion for filling replenishing looms, comprising in its construction, a 10 feeler slide having a feeler toe or point adapted to contact with and sink into the filling on a carrier, a detector having a detector head to contact with the filling on the carrier and tilt the detector when the said 15 feeler toe or point has sunk into a working supply of filling, and an indicator head to indicate the presence of filling beyond the points where the detector head and toe act and to tilt the detector when it fails to be 20 tilted by the detector head and there yet remains a working supply of filling on the carrier.

6. A feeler motion for filling replenishing looms, comprising, in combination, a feeler 25 slide having a feeler toe or point constructed and arranged to contact with and sink into the filling on a carrier, a detector having a detector head at one side of the feeler toe or point to contact with the filling on the carrier and tilt the detector when the feeler toe has sunk into the filling, and an indicator head extending at the opposite side of the feeler toe or point to indicate the presence of filling beyond the points where the 30 detector head and feeler toe act and to tilt the detector when it fails to be tilted by the detector head and there yet remains a working supply of filling on the carrier.

35 7. A feeler motion for filling replenishing looms, comprising, in combination, a feeler 40 slide having a feeler toe or point constructed and arranged to contact with and sink into the filling on a carrier, a detector having a detector head at one side of the feeler toe or point to contact with the filling on the carrier and tilt the detector when the feeler toe has sunk into the filling, and an indicator head having an inclined edge and extending

50 at the opposite side of the feeler toe or point to indicate the presence of filling beyond the points where the detector head and feeler toe act and to tilt the detector when it fails to be tilted by the detector head and there yet remains a working supply of filling on the carrier.

55 8. In a device of the character described, the combination of a feeler slide having a feeler toe, and a detector pivotally mounted on the slide and having a head provided at one side of the feeler toe with a straight edge and at the opposite side of said feeler toe with an inclined edge.

60 9. In a feeler motion for filling replenishing looms, the combination of a feeler having an end or toe, a detector adjacent said end or toe and adapted to be moved by the filling on the carrier when the end or toe sinks into said filling a predetermined amount, and means acting at a point beyond the detector and adapted to move said detector when it fails to be moved by the filling adjacent thereto and there yet remains a working supply of filling at a point beyond the detector.

65 10. In a feeler motion, the combination of a feeler slide 8 having a toe or end 19 adapted to sink into the filling when a working supply is on the carrier opposite thereto, a detector having a head 28 to contact with the filling and be moved thereby when the toe or end 19 sinks into the filling, and an indicator 29 acting at a point beyond the head 28 to indicate the presence of a working supply of filling at said point and adapted to move said detector when a working supply 70 of filling is present at said point and the working supply opposite the head 28 has become exhausted.

75 In testimony whereof, I have signed my name to this specification, in the presence of 90 two subscribing witnesses.

JOHN HENDRY.
